GAME BOARD

Otis F. Caldwell, 2427 Roslyn Ave., Charlotte, N.C.

Filed Feb. 5, 1960, Ser. No. 59,280

Term of patent 7 years

(Cl. D34—5)

The figure is a top plan view of a game board of conventional thickness showing my new design.

The dominant features of my design reside in the portions shown in full lines.

I claim:

The ornamental design for a game board, as shown and described.
